US00D934186S

(12) **United States Design Patent** (10) **Patent No.:** **US D934,186 S**
Omote (45) **Date of Patent:** **** Oct. 26, 2021**

(54) **MOTOR CONTROLLER**

(71) Applicants: **KABUSHIKI KAISHA TOSHIBA, Tokyo (JP); TOSHIBA ELECTRONIC DEVICES & STORAGE CORPORATION, Tokyo (JP)**

(72) Inventor: **Hirofumi Omote, Tokyo (JP)**

(73) Assignees: **KABUSHIKI KAISHA TOSHIBA, Tokyo (JP); TOSHIBA ELECTRONIC DEVICES & STORAGE CORPORATION, Tokyo (JP)**

(**) Term: **15 Years**

(21) Appl. No.: **29/717,177**

(22) Filed: **Dec. 16, 2019**

(30) **Foreign Application Priority Data**

Jun. 18, 2019 (JP) 2019-013396

(51) LOC (13) Cl. **13-03**

(52) U.S. Cl.

USPC **D13/162; D13/110; D13/123; D15/5**

(58) **Field of Classification Search**

USPC D13/101, 110, 122, 123, 124, 126, 162, D13/184, 199

CPC .. H05K 7/20; H05K 7/20845; H05K 7/20872; H05K 7/2089; H05K 7/20927
